Primary Examiner — Marissa J Cash(74) *Attorney, Agent, or Firm* — Lawrence Youst PLLC(57) **CLAIM**

The ornamental design for a pair of aircraft wings, as shown and described.

DESCRIPTION

FIG. 1 is a perspective view of a pair of aircraft wings; FIG. 2 is a top plan view of the pair of aircraft wings of FIG. 1;

FIG. 3 is a bottom plan view of the pair of aircraft wings of FIG. 1;

FIG. 4 is a right side elevation view of the pair of aircraft wings of FIG. 1;

FIG. 5 is a left side elevation view of the pair of aircraft wings of FIG. 1;

FIG. 6 is a front elevation view of the pair of aircraft wings of FIG. 1; and,

FIG. 7 is a rear elevation view of the pair of aircraft wings of FIG. 1.

The broken lines in the drawings represent unclaimed environmental subject matter and form no part of the claim.

1 Claim, 6 Drawing Sheets(56)
